UNITED STATES PATENT OFFICE.

WALTER L. FINTON, OF APPLETON, WISCONSIN.

GRAIN-BIN.

No. 867,962.

Specification of Letters Patent.

Patented Oct. 15, 1907.

Application filed May 18, 1906. Serial No. 317,416.

To all whom it may concern:

Be it known that I, WALTER L. FINTON, residing in Appleton, in the county of Outagamie and State of Wisconsin, have invented new and useful Improvements in 5 Grain-Bins, of which the following is a description, reference being had to the accompanying drawings, which are a part of this specification.

My invention has relation to improvements in grain bins.

10 One of the primary objects of the invention is to provide a grain tank, preferably fire-proof, subdivided into bins of such shape that they may be completely filled and completely discharged by means of spouts.

Another object of the invention is to provide a grain 15 tank divided into bins, each one of which may be discharged through the side of the tank, at or near lowest point of bin, into a spout, or into any one of several spouts.

Another object of the invention is to provide a grain 20 tank divided into bins, each bin of a capacity approximating a car load, any one of which bins may be discharged independently of the others, and each one of said bins being located at the proper height to be discharged into a car, or other device, without further elevating.

A further object of the invention is to provide a grain tank divided into bins, each bin capable of containing approximately a car load of grain, and any one of which may, by means of a conducting spout, be discharged 30 simultaneously with any number of bins into a common receptacle, or on to a moving belt, or to any other form of conveyer, for delivery into a car, bulk storage tank, or other receptacle, in a thoroughly blended mass.

A still further object resides in the arrangement of 35 bins of the above described character in a circle, or in square, oblong, or other convenient form, whereby the said bins are made to constitute the sides of an inclosure which may be covered, thereby making a working house into some convenient part of which spouts leading from the several bins may be directed and discharged on to a moving belt, thereby securing a more perfect blending of a number of kinds or qualities of grain than is possible by methods now in use.

With the above, and other incidental, objects in view, 45 the invention consists of the devices and parts, or their equivalents, as hereinafter set forth.

In the accompanying drawing, Figure 1 is a longitudinal, vertical, sectional view of a grain bin constructed in accordance with my invention, certain parts being 50 broken away; Fig. 2 is an elevation of the grain bin at right angles to Fig. 1, the view illustrating a modification, wherein an endless belt upon which the different discharge spouts are adapted to discharge is employed; Fig. 3 is a plan view of Fig. 2; Fig. 4 is a view showing 55 the bins arranged in a gang; and Fig. 5 is a view of a modified form of construction.

Referring to the drawing, the numeral 5 indicates a grain tank, preferably of fire-proof construction, and also preferably of cylindrical form in cross section, although a bin of elliptical, square, rectangular, or other form in cross section, may be employed, if desired. The ordinary upright cylindrical fire-proof grain tank may be utilized, such as used for storage of bulk grain. The tank is divided into a series of separate grain bins by means of sloping or inclined floors or partitions 6. In the drawing I have shown six of these sloping or inclined floors, subdividing the tank into five grain bins, indicated by the numeral 7. It will be understood that these floors are arranged so as to slope or be on a gradual decline from one side of the tank downwardly to the opposite side thereof, so that the highest point of each floor is on one side of the tank, and the lowest point of each floor on the opposite side of the tank. It will also be observed that each successive floor is parallel with the preceding floor.

Leading to the upper portion of each bin is a feed pipe 8, and leading from the opposite side of each bin, from a point just above the flooring and consequently at the lowest point of the bin, is a discharge pipe 9. The lower ends of these discharge pipes are alined in 80 a horizontal row, and are sufficiently high to provide for discharging into a car, on to a movable belt, or on to any other form of conveyer.

In Fig. 1 of the drawing, I show one of the discharge pipes adapted to discharge into an ordinary grain car 85 10 (shown in dotted lines) through the usual side opening of said car. In order that the discharge tube may discharge into the interior of the car, and yet not interfere with the car's travel on the track to a position to receive the grain, the discharge end of each tube 90 terminates a desired distance from the track, and when the car is run up to position, a short spout 11 which may be flexible, is connected to the end of the discharge tube, or if preferred, may be non-flexible, and have a swiveled connection with the end of the discharge 95 tube, and thereby lengthen said tube sufficiently to cause it to extend into the car through the side opening thereof.

Fig. 2 of the drawing shows the device arranged to discharge onto a traveling endless belt or conveyer 12 100 which passes around a pulley 13, whose axle is journaled in suitable bearings 14 extending from the supporting frame of the tank. This belt leads to and around another pulley (not shown), and the grain discharged from the belt may be caught by a chute (not shown) and conveyed by said chute to a car, or to a bulk storage tank, or other receptacle.

The several feed tubes 8 herein before referred to extend upwardly to the top of the tank, where the grain is discharged into them by the ordinary means employed for that purpose.

For the purpose of obtaining convenient access to the

interior of each bin so that the bins may be readily cleaned, the wall of the tank is provided with a number of manholes 15, one for each bin, and provided with a suitable cover 16.

5 Fig. 4 of the drawing shows a gang of five of the tanks arranged in a circle, to form a circular inclosure 20, with an entrance 21 thereto. They may, however, be arranged in square, oblong, or other form, to form the sides of an inclosure, and when so arranged may be 10 covered to provide a working house, in some convenient part of which spouts leading from the several bins may be directed and discharge onto a moving belt, thereby making possible a more perfect blending of a number of kinds or qualities of grain, and a perfect 15 blending of a greater number of different kinds or qualities of grain than is possible by methods now in use.

Each discharge tube is provided with a valve 17. By this provision, only one tube at a time may be opened up so as to permit the discharge from only one 20 bin, or the valves of several of the tubes may be opened, so as to permit discharge from a plurality of the bins, or all the valves may be opened so as to permit discharge from all the valves simultaneously.

In feeding the grain to the different bins, a means 25 will be provided at the upper end of each feed spout for delivering the grain into any particular spout, and there are a number of methods at present employed in elevators which will answer every purpose. In this way the different bins are filled, and they may be 30 emptied by opening the valves of the discharge tubes in the manner herein before fully pointed out.

By my invention, it will be evident that a most convenient construction is provided, whereby the tank is divided into separate bins, each, preferably, of a 35 capacity to hold a car load of grain, and of such shape that they may be completely filled and completely discharged by means of spouts, and the construction is also such that any one of the bins may be discharged independently of the other, or any number discharged 40 simultaneously, or all the bins discharged simultaneously, either into a common receptacle, or onto a moving belt, or other conveyer, for delivery into a car, bulk storage tank, or other receptacle, in a thoroughly blended mass. Furthermore, the invention is of such 45 character as to provide for the arrangement of the tanks in the manner shown in Fig. 4 to secure the advantages herein before fully pointed out.

It will also be observed that with my invention, it is possible to keep grain that is out of condition, that is, 50 grain which is in a heated condition and therefore compact and incapable of discharging through the discharge spouts, in separate bins, and removed from said bins by being shoveled out through the manholes. If grain which is out of condition is put into a bin with 55 other grain that is in condition, it will result in great damage. In small bins ordinarily employed in wooden structures, it is necessary, when grain is heated and in compact condition, to shovel the grain out from the top, or to sack it.

60 In the operation of elevators, it is customary to weigh the grain before it is loaded into a car, in order that the actual weight of the contents of a car may be known. I, therefore, in Fig. 5 of the drawings, show a form of

construction wherein a number of the bins are located at such height that any one of them may discharge 65 into a scale hopper, from which hopper leads a conduit adapted for discharging into a car, or into any other desirable receptacle. In this form of the device, three of the bins are shown at such height as to be capable of discharging into the scale hopper, and the remaining 70 three of the bins are not sufficiently high to discharge into the hopper but are adapted to discharge onto a moving belt. This weighing hopper is indicated by the numeral 18, and should be of a capacity sufficient to weigh a car load in one draft. This car load may 75 come from one bin, or from a number of bins. From the converged bottom of the hopper leads a pipe or conduit 19, which is shown as extending through the side opening of the grain car 10.

The other lower bins shown in Fig. 5 have the discharge pipes or spouts 9 thereof extending to a point just above a movable endless belt 20.

While I prefer that the bottom of each bin should be on a slant from one side of the tank to the other, yet, I desire, at this time, to direct attention to another 85 very important feature of my invention, viz., the means for discharging the bins through the side of the tank, at or near the lowest point of each bin, whereby the grain is so discharged as to make it possible to direct it to any particular point, by reason of the height or 90 distance from the ground of the point of discharge from the bin. It will be readily appreciated that in carrying out this object the particular construction of the bin bottom as shown in the drawings is not absolutely essential, inasmuch as a hoppered bottom, or any other 95 desired form, will answer so long as a means is provided for discharging the bin through the side of the tank, and at or near the lowest point of the bin. Under this construction each discharge spout leading from a bin may extend outwardly only a short distance beyond 100 the side of the tank, and may be arranged to discharge into any one of a series of pipes leading to different points of delivery, either by having a swivled extension on the end of the discharge pipe, or by having the series of pipes so arranged as to be adjustable in order 105 to bring the upper end of any one of said pipes into register with the discharge spout.

What I claim as my invention is:

1. A tank for the storage of grain and the like, consisting of an inclosure having a plurality of inclined floors, in 110 single planes, forming bins each having one point higher and one point lower than any other point thereof, each of said bins having an opening in its side wall at the highest point and another at its lowest point, substantially as described.

2. A tank for the storage of grain and the like, consisting of an inclosure having a plurality of inclined floors, in single planes, forming bins each having one point higher and one point lower than any other point thereof, each of said bins having an opening in its side wall at the highest point and another at its lowest point, separate feeding means leading to the opening located at the highest point of each bin, and separate discharging means leading from the opening located at the lowest point.

In testimony whereof, I affix my signature, in presence 125 of two witnesses.

WALTER L. FINTON.
